FOOD STRAINER FOR USE WITH BOWLS OR THE LIKE

Elyon Elaine Berman, Los Angeles, Calif., assignor to Burroughs Manufacturing Corporation, Los Angeles,
Calif., a corporation of California

Filed Aug. 22, 1958, Ser. No. 52,345

Term of patent 14 years

(Cl. D44—1)

FIG. 2.

Fig. 1 is a top perspective view of a food strainer for use with bowls or the like showing my new design; and Fig. 2 is a bottom perspective view thereof.

The drain bowl shown in broken lines in Fig. 1 is for purposes of illustration only.

I claim:

The ornamental design for a food strainer for use with bowls or the like, substantially as shown and described.
